LIQUID DISPENSING APPARATUS

Filed May 26, 1926

UNITED STATES PATENT OFFICE.

WILLIAM F. BRANDT, OF FORT WAYNE, INDIANA, ASSIGNOR TO WAYNE COMPANY,
OF FORT WAYNE, INDIANA, A CORPORATION OF INDIANA.

LIQUID-DISPENSING APPARATUS.

Application filed May 26, 1926. Serial No. 111,760.

My invention relates to liquid dispensing apparatus and particularly to means for completely draining the liquid in the elevated reservoir back to the storage tank. In such apparatus the elevated reservoir is made of glass, hence this particular type is generally called visible dispensing apparatus, and they are used principally for dispensing gasoline.

To decrease fire hazard some means for completely draining the contents of the elevated reservoir back to the storage tank is usually required, and one means is through the discharge hose and nozzle into the overflow pipe and thence to the storage tank.

15 The main idea is set forth in the patent to Edward N. Kern, No. 1,210,812, issued January 2nd, 1917.

The principal object of this invention is to provide means for securing the hose nozzle 20 to the projection from the overflow pipe, when the former is inserted in the latter for draining the elevated reservoir, so that the nozzle cannot become accidentally displaced or be removed by unauthorized persons.

25 Another object is to make such a joint between the hose nozzle and its socket in the overflow pipe as to prevent water drainage into the storage tank therethrough, gas escaping therefrom or the insertion of foreign 30 material of any kind by malicious or mischievous persons.

Another object is to provide means for keeping the opening to the overflow pipe closed when the hose nozzle is removed therefrom.

35 In the particular embodiment of my invention selected for illustration:—

Figure 1 is an elevation of a visible dispensing apparatus of the so called wet hose 40 type, shown from the discharge and drain back side, with the hose nozzle in drain-back position,

Fig. 2, is an enlarged section thru a portion of the lower part of the pedestal, exposing the lower part of the drain-back tube 45 and the lateral projection therefrom, the top of the projection shown with the cap locked thereon as it would be when the apparatus is in use, these parts being shown in axial 50 section, and

Fig. 3, an enlarged detail, shows the lower part of the hose with valved nozzle attached.

Referring now to the drawings, A is the pedestal of a visible dispensing apparatus, 55 with base α and cap α^1 which forms the bottom

head for the cylindrical glass reservoir C, which is surmounted by the top head α^2 , the reservoir C being held securely in place by tie rods α^3 .

The reservoir C is filled with gasoline from 60 an underground storage tank, not, shown, by means of a pump P, through a supply-pipe, designated as p below the pump and p^1 above it.

An overflow pipe O terminates within the 65 reservoir at such a height as when the reservoir is filled ready to serve customers, the quantity equals the maximum amount to be dispensed at one time, generally five or ten gallons; and it is adapted to convey excess 70 liquid back to the storage tank.

From a T, α in the overflow pipe extends to the side thru the pedestal A an angular projection α^4 , terminating at the top in a fitting α^2 , with an annular boss α^3 upon which seats 75 a packing washer α^4 , when the cap α^5 is closed and secured by the lock α^6 as it is when the apparatus is in service.

Pins α^7 extending thru the sides of the fitting α^2 , protrude inwardly a short distance 80 so that they will enter the bayonet slots d on the sides of the nozzle D, when the cap α^5 is raised and the nozzle is inserted in the fitting α^2 . When the nozzle is so inserted, it is pressed down and rotated to the left, the pins α^7 entering the oblique portion d^1 of the bayonet slots d causing the packing washer α^4 to seal the joint between the boss α^3 and the nozzle flange d^2 , making a joint that will be gas tight. When in this position the 85 nozzle is locked against displacement by the padlock d^3 which secures the guard d^4 to a bracket α^8 on the pedestal.

It will be noted that the nozzle D has a valve d^7 shown closed in Fig. 3, and open in 95 Fig. 1, because the valve lever d^6 is depressed by the bracket α^4 . The cap α^5 is so formed as to be self closing when the nozzle is removed. When in service the fitting α^2 is always closed whether locked or not, and when locked up 100 for the night the hose valve is always open to ensure complete draining of the glass reservoir C thru the hose H.

I do not wish to be limited to the precise mechanism herein shown and described, but 105 conceive as within the scope of my invention, all forms readable on the claims.

I claim as my invention and desire to secure by Letters Patent of the United States:

1. A liquid dispensing apparatus compris- 110

ing in combination an elevated container from which liquid is dispensed, a serve hose connected at one end to said container, a discharge nozzle on the other end of said hose, 5 said hose adapted to completely drain said container, a drain-back pipe adapted to drain back to storage liquid in the container in excess of the maximum quantity to be served at one discharge, a pipe connected to said 10 drain-back pipe below said container and adapted to receive said discharge nozzle, said pipe open at its outer end, a self closing cap normally keeping said open end closed, pins extending internally from the inner wall of 15 said pipe connection and near its open end, a valve in said discharge nozzle, a flange and a packing washer on said nozzle, bayonet slots on said nozzle adapted to coact with said pins in said pipe connection, and means for maintaining said nozzle valve in open position 20

when said nozzle is inserted in said pipe connection.

2. A liquid dispensing apparatus, comprising an elevated reservoir from which liquid is dispensed, a hose attached to said elevated reservoir to drain it, a nozzle for said hose, a drain-back pipe adapted to return to storage liquid in said reservoir in excess of the maximum quantity to be served at one dispensing discharge, an open conduit connection below 25 said reservoir extending laterally from said drain-back pipe and having an open end adapted to receive the discharge end of said nozzle and a weighted cap keeping the open end of such connection closed except when 30 held open.

In testimony whereof I have hereunto set my hand.

WILLIAM F. BRANDT.
